UNITED STATES PATENT OFFICE.

EUGEN VON MALTITZ, OF THE HAGUE, NETHERLANDS, ASSIGNOR TO THE FIRM J. BRÜNING & SOHN AKTIEN-GESELLSCHAFT, OF POTSDAM, NEAR BERLIN, GERMANY.

VENEER BOX AND METHOD OF MANUFACTURING THE SAME.

Application filed October 29, 1926, Serial No. 145,064, and in Germany September 9, 1926.

This invention relates to a method of manufacturing cases or boxes for cigarettes and containers of any kind for packing purposes from veneer, composite and shuted wood panels. Many efforts have already been made to commercially manufacture in a continuous process containers from veneer, but it has not been possible to produce containers free from rupture from the very delicate thin plywood, as on account of the material being brittle the bottom and the edges split during bending or beading.

Efforts have also been made to work the plywood for the manufacture of containers in a wet state to obtain a certain flexibility of the structure for the purpose of preventing splitting or breaking during the bending of the edges. The disadvantage of this wet working, however, is the fact that after drying the finished product shrinks and the container assumes a bad appearance and an unequal form.

The object of this invention is to obviate all these disadvantages and to provide a method which allows a most simple, cheap and reliable manufacture of containers free from rupture.

The new method may for example be carried out by the means shown in the accompanying drawing although any other means suitable for the purpose may be used without departing from the invention.

Fig. 1 is a perspective view showing applicant's device, and Figs. 2 and 3 are cross-sections of modified forms of the steam nozzle.

The thin plywood serving for the manufacture of the containers is cut in bands or breadths the dimensions of which correspond to the size and depth of the container (bottom or cover). In the drawing the plywood S is shown diagrammatically. S¹ and S² show the portions of the plywood S which form the longitudinal side parts. At a suitable point the plywood running or moving in special guides upon a working table is brought upon or under a steam blast g the nozzle e of which is formed to correspond to

the container to be made. The steam jet impinges upon the plywood along the lines 1, 2, 3, 4 and softens the plywood at these lines sufficiently and in such a manner that the parts of the plywood bounded by the lines 1, 2, 3, 4 maintain their solid structure. After the steam has sufficiently acted upon the plywood the steam blast is lifted a little by any suitable device, whereby the mandrel f provided upon the steam tubes is gently pressed into the plywood at the lines 1, 2, 3, 4 softened by the steam and the bending or beading of the edges a, b, c, d without splitting in the next step of the manufacture is prepared. The mandrel f' (Fig. 3) may also be so made as to simultaneously form the nozzle e' instead of being constructed as a special device as shown in Fig. 1.

After a corresponding preparing under or in connection with the steam blast the veneer foil S is fed upon the working table underneath the press which carries the patrice and matrice in the form of the container to be made and which by suitable pressure effects, as illustrated in the lower part of Fig. 1, the manufacture of an upper or lower part of the container, the matrix hereby pressing into the softened lines 1, 2, 3, 4 and forming from the parts S¹, S², S³, S⁴ the edges bounded by a, b, c, d.

What I claim is:

1. In a method of making box parts from plywood by bending such material, comprising cutting the material into sheets having dimensions corresponding to certain dimensions of the finished box parts, simultaneously moistening by steam under pressure the plywood on lines on which the material is to be bent and bending the material along the lines thus moistened to form said box parts to shape.

2. In a method of making box parts as claimed in claim 1, in which there is employed a steam blower corresponding in shape to the outline of the bottom of the box part.

In testimony whereof I affix my signature.

DR. EUGEN VON MALTITZ.
